(57) **CLAIM**

The ornamental design for a load-mountable lift eye, as shown and described.

DESCRIPTION

FIG. 1 is a top-front perspective view of an ornamental design of a load-mountable lift eye;

FIG. 2 is a front elevational view thereof, the rear elevational view being a mirror image of the front elevation view;

FIG. 3 is a left side elevational view thereof, the right side elevational view being a mirror image of the left side elevation view;

FIG. 4 is a top plan view thereof;

FIG. 5 is a bottom plan view thereof;

FIG. 6 is a further top-front perspective view thereof, wherein an optional mounting bolt, bushing and retaining ring are illustrated in broken lines and do not form part of the claimed design; and,

FIG. 7 is a cross-sectional view thereof taken along line 7-7 of FIG. 6.

The broken lines in the Figures represent environmental structure and form no part of the claimed design.
